ABSTRACT

A vehicle windscreen is provided with electrical antenna conductors in the form of a row of open loops connected to at least one straight horizontal arm. The loops lie in an area corresponding to the rear view mirror position. In situ in a vehicle the loops do not project below the lower edge of the rear view mirror and the loop do not project beyond the lateral edge of the mirror. Between three and 12 loops may be provided and they may be connected to a second horizontal conductor arm. A vertical conducting arm may also be connected to the row of loops. The conductors may lie on the inner surface of the windscreens.

WINDSHIELD ANTENNA

BACKGROUND OF THE INVENTION

The invention relates to vehicle windscreens and in particular to a vehicle windscreen including electrical antenna conductors.

Vehicle windscreens are known which are provided with electrical antenna conductors. Some difficulties have arisen in arranging the conductors so as to provide sufficient signal strength for a radio receiver while avoiding undesirable obstruction of vision through the windscreens.

It is an object of the present invention to provide an improved windscreen incorporating electrical antenna conductors.

SUMMARY OF THE INVENTION

The present invention provides a vehicle windscreen provided with electrical antenna conductors, said conductors including a plurality of open loops located in the area corresponding to the rear view mirror position, said loops being joined in succession to form a row of loops extending along an upper part of the windscreens and spaced from the upper edge of the windscreens and at least one straight horizontal arm being connected to one end of the row of loops also extending along the upper part of the windscreens, the loops forming the antenna being located in the area behind the rear view mirror position so that the loops do not project substantially beyond the lateral edges of said area and the height of the loops in the row being such that they do not project substantially below the lower edge of the said area.

Such an arrangement of antenna conductors enables the aerial to provide sufficient signal strength for an AM radio receiver and the loops do not project sufficiently far down the windscreens to interfere with vision through the windscreens.

All the loops forming the antenna are located in the area corresponding to the rear view mirror position so that the loops do not project substantially beyond the lateral edges of the rear view mirror. This reduces interference with vision to a minimum.

Preferably the antenna conductors comprise from three to 12 loops and in some cases from six to 12 loops. Preferably the loops are not less than 1 inch high. In this way, satisfactory signal strength may be provided.

Preferably the length of the row of loops is greater than the height of the loops. Such an arrangement is of practical convenience in that rear view mirrors normally have greater width than depth. In general, allowing for the variation in size and position of rear view mirrors the loops lie within an area 9 inches wide by 4 inches deep at the maximum and spaced from the upper edge of the windscreens by a distance not greater than 3 inches. In some cases two straight horizontal arms may be provided, one at each end of the row of loops. Additionally, a straight vertical arm may be connected to the row of loops.

BRIEF DESCRIPTION OF THE DRAWINGS

FIG. 1 shows a vehicle windscreen with a known T-shaped aerial, not embodying the present invention,

FIG. 2 shows a further embodiment of the invention in which a single horizontal arm is added to the row of loops,

FIG. 3 shows a further embodiment of the invention in which two horizontal arms are connected to the row of loops,

FIG. 4 shows a further embodiment of the invention in which the antenna conductors consist of a row of loops together with one horizontal arm and one vertical arm,

FIG. 5 shows a further embodiment of the invention in which two horizontal arms and one vertical arm are added to the row of loops, and

FIG. 6 shows schematically a vehicle incorporating a windscreen embodying the invention.

DESCRIPTION OF THE PREFERRED EMBODIMENTS

In FIG. 1, a vehicle windscreen 11 is shown with a known aerial arrangement for a radio receiver. The aerial consists of two horizontal conducting arms 12 and 13 joined to a vertical arm 14 having a suitable termination 15 at its lower end for use in connecting the aerial to a radio receiver.

FIGS. 2 to 5 show various alternative embodiments of the present invention which all differ from the arrangement shown in FIG. 1 in that the antenna conductors include as well as a horizontal arm 18, a plurality of open loops joined in succession to form a row of loops in the upper central part of the windscreens and in the area normally behind a rear view mirror. In each of the examples in FIGS. 2 to 5, the row of loops 16 extends horizontally along the upper part of the windscreens 11 so that the upper edge of the loops is spaced from the top of the windscreens and the lower edge of the loops does not project below the lower edge of the rear view mirror position in the motor vehicle. In each of FIGS. 2 to 5, the position of the rear view mirror is shown by broken lines 17. In FIG. 2, a single straight horizontal arm 18 is connected to one end of the row of loops 16 and extends parallel to and spaced from the upper edge of the windscreens. A suitable termination 15 is provided at the end of the arm 18 remote from the row of loops 16. Alternatively the termination 15 may be provided at the free end of the row of loops 16. Such an alternative is marked 15a in FIG. 2. In FIG. 3, a second straight horizontal arm 19 is connected to the other end of the row of loops 16. The examples shown in FIGS. 4 and 5 are generally similar to those shown in FIGS. 2 and 3 except that a vertical arm 14 is in each case connected to the row of loops 16. The upper end of the vertical arm is in each case connected to the row of loops mid-way along the row of loops. Although in FIGS. 4 and 5 the termination 15 is shown at the end of the horizontal arm 18, it may alternatively be provided at the free end of the row of loops 16 (FIG. 4) or at the end of the other horizontal arm (FIG. 5) or at the bottom of the vertical arm (FIGS. 4 and 5). Alternatively in all the arrangements of FIGS. 2, 3, 4 and 5 the termination 15 may be provided at a point intermediate the ends of the row of loops 16, preferably at the centre of the row of loops 16, as marked 15b in FIG. 3.

In each of the examples shown in FIGS. 2 to 5, the loops 16 all lie in a single plane with each loop consisting of a rounded S-shaped portion lying on its side. The number and size of loops may be varied to suit the vehicle and radio receiver being used. The shape of the loops may also be varied, for example the S-shape could be squared up or a straight sided zig-zag could be

employed. Whilst the loops employed in a given antenna will usually be identical with one another this is not necessarily so. It is desirable for the loops 16 to lie wholly within the area 17 of the rear view mirror. Furthermore, the number and size of loops may be varied to suit the particular radio receiver used.

The following Table 1 gives nine examples of the size and location for the standard fitting of rear view mirrors currently used in British cars. The units are in inches and in each case the mirror is situated centrally across the width of the windscreen.

taken at a location where the signals were comparatively very strong and with the antenna coupled to the voltmeter by 6 inches of low loss cable. Example 1 given in the Table is the known configuration of aerial 5 shown in FIG. 1 of the accompanying drawings. Examples 2 to 10 show various examples in accordance with the present invention, in each case the height of the loops was 3 inches and the length of the row of loops was 6 inches.

10 In the various examples 2 to 10, the number of loops, height of loops and length of row of loops was varied.

TABLE 1

		Example	Width	Height	Spacing from top of Windscreen
Austin Morris	Mini	1	5½	2	1½
	1100	2	7	3	1
	1800	3	7	2	2
	MGB	4	7	1½	2
Triumph 1300		5	6	3	2
Rover 2000		6	8	1½	2½
Ford Escort		7	7	2	2
Cortina		8	7	3	1
Vauxhall Viva		9	6	2	2

In order that the loops 16 do not project substantially beyond the lateral edges or below the lower edge of the rear view mirror, the loops will in general lie within an area not more than 9 inches wide by 4 inches deep, the upper edges of the loops being spaced up to 3 inches from the top of the windscreen. The actual area taken up by the loops on any particular windscreen will however be determined by the size and position of the rear view mirror to be fitted. The length of the horizontal arms 18 and 19 and the vertical arm 14 should be as long as is possible within the confines of the windscreen, but the arms require to be terminated at least 2 inches from the edge of the windscreen.

The following Table 2 gives the relative signal strengths achieved with different configurations of aerial. The Table gives the signal strength in millivolts as measured with a radio frequency voltmeter of the heterodyne type for the A.M. transmissions of BBC Radio 2 at a frequency of 0.20 MHz. The measurements were

30 Furthermore, the examples covered the different arrangements shown in FIGS. 2 to 5 and the location of the terminal connection 15 differed in the various examples.

In the above examples, it is considered that the signal strengths represent good reception in being greater than a value of 19.0 millivolts.

Overall it is preferred to use from three to 12 loops not less than 1 inch in height.

35 In the case of a laminated windscreen, the antenna conductors may be positioned in one of the glass/interlayer interfaces or preferably on one of the exposed glass surfaces, particularly that which will be inside the vehicle. In the case of a windscreen formed from a single sheet of toughened glass, the antenna conductors are preferably positioned on the surface that is to be inside the motor vehicle. It is however possible to locate the conductors on the outer surface.

40 The conductors may be wire or a deposit of some conducting material although wire can only be used with a laminated windscreen when it will usually be positioned in one of the glass/interlayer interfaces. The wire may for example be 24 gauge copper wire, that is wire having a diameter of 22 thousandths of an inch. If a conducting deposit is used, this may be applied by a silk screen printing process using an ink which is fired onto the glass surface and preferably that surface which will lie inside the vehicle. The ink may contain a silver compound and a low melting point glass frit as referred to in British Pat. No. 1145367. Suitable commercially available inks are supplied for example by Degussa under the reference number 314E and by DuPont under reference numbers EX 8438R and EX 8439R and EX 8448R. Alternatively an ink formed of a silver oxide organic silver salt complex supplied by Englehard may be used. The width of the printed line is in the region of 0.4 millimetres and may for example be 0.35 millimetres. Firing of the ink occurs during heating the glass for bending and toughening when the glass is at approximately 650°C.

45 FIG. 6 shows the use of the invention in a motor car 20. The car 20 has a windscreen 11 incorporating an

tenna conductors having the general arrangement described with reference to FIG. 3. The loops 16 lie wholly behind a rear view mirror 21 which is fixed adjacent the upper central part of the windscreens. The terminal 15 is connected by a suitable conductor to an A.M. radio receiver mounted within the vehicle.

The invention is not limited to the details of the foregoing examples.

We claim:

1. A vehicle windscreens provided with electrical antenna conductors, said conductors including a plurality of open loops located in the area corresponding to the rear view mirror position, said loops being joined in succession to form a row of loops extending along an upper part of the windscreens and spaced from the upper edge of the windscreens and at least one straight horizontal arm being connected to one end of the row of loops also extending along the upper part of the windscreens, the loops forming the antenna being located in the area behind the rear view mirror position so that the loops do not project substantially beyond the lateral edges of said area and the height of the loops in the row being such that they do not project substantially below the lower edge of the said area.

2. A vehicle windscreens according to claim 1, in which the antenna conductors comprise from six to 12 loops.

3. A vehicle windscreens according to claim 1, in which a second straight arm is connected to the loops and the antenna conductors include from three to 12 loops.

4. A vehicle windscreens according to claim 1, in which the loops are not less than 1 inch high.

5. A vehicle windscreens according to claim 1, in which the length of the row of loops is greater than the height of the loops.

6. A vehicle windscreens according to claim 1, in which the loops lie within an area 9 inches wide by 4 inches deep, the area lying centrally across the width of the windscreens.

7. A vehicle windscreens according to claim 6, in which the upper edge of the loops is spaced from the upper edge of the windscreens by a distance not greater than 3 inches.

8. A vehicle windscreens according to claim 1, in which a straight vertical arm is connected to the row of loops.

9. A vehicle windscreens according to claim 1, including two straight horizontal arms one connected to each end of the row of loops.

10. A vehicle windscreens according to claim 1, in which the end of an arm remote from the row of loops is used as a terminal for connecting the antenna to a receiving circuit.

11. A vehicle windscreens according to claim 1, in which a connecting terminal is provided at a free end of the row of loops.

12. A vehicle windscreens according to claim 1, in which a connecting terminal is provided at a point intermediate the ends of the row of loops.

13. A vehicle windscreens according to claim 1, in which the conductors are positioned on the inner surface of the windscreens.

14. In a motor vehicle a windscreens according to claim 1, together with a rear view mirror, the loops in the antenna conductors being located in the area lying behind the rear view mirror as seen by the driver.

15. A vehicle having a windscreens as claimed in claim 1, together with a rear view mirror, the loops in the antenna conductors being located in the area lying behind the rear view mirror as seen by the driver.
